UNITED STATES PATENT OFFICE

153,039

DESIGN FOR A BRACKET

Roy S. Sanford, Woodbury, Conn., assignor to The
Autoyre Company, Incorporated, Oakville,
Conn., a corporation of Connecticut

Application March 27, 1947, Serial No. 137,937

Term of patent 14 years

(Cl. D4—3)

To all whom it may concern:

Be it known that I, Roy S. Sanford, a citizen of the United States, residing at Woodbury, in the county of Litchfield and State of Connecticut, have invented a new, original, and ornamental Design for a Bracket, of which the following is a specification, reference being had to the accompanying drawing, forming a part thereof, in which:

Fig. 1 is a perspective view of a bracket, embodying my new design;

Fig. 2 is an enlarged face view of the bracket shown in Fig. 1;

Fig. 3 is a side elevational view of the bracket shown in Fig. 2; and

Fig. 4 is a top view of the bracket shown in Fig. 2.

I claim:

The ornamental design for a bracket, substantially as shown.

ROY S. SANFORD.
